(57) CLAIM

The ornamental design for a covered filter basket, as shown and described.

DESCRIPTION

FIG. 1 is a top perspective view of a covered filter basket; FIG. 2 is a bottom perspective thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view thereof.

The broken lines in the drawings depict environmental subject matter only and form no part of the claimed design.
